UNITED STATES PATENT OFFICE.

WARD S. IRELAND, OF ST. LOUIS, MISSOURI, ASSIGNOR TO NATIONAL SHORTHAND MACHINE COMPANY, OF ST. LOUIS, MISSOURI, A CORPORATION OF DELAWARE.

SHORTHAND-MACHINE.

1,283,198.

Specification of Letters Patent. Patented Oct. 29, 1918.

Application filed November 18, 1916. Serial No. 132,074.

To all whom it may concern:

Be it known that I, WARD S. IRELAND, a citizen of the United States of America, a resident of the city of St. Louis, State of Missouri, have invented certain new and useful Improvements in Shorthand-Machines, of which the following is a full, clear, and exact description, reference being had to the accompanying drawings, forming a part of this specification.

My invention relates to improvements in typewriting machines, and the novel features of the invention are particularly adapted for use in shorthand machines. One of the objects of the invention is to produce a shorthand machine having an identification device for printing a distinguishing mark, or marks, serving as means for identifying the stenographer or dictator, or both.

Prior to this invention, shorthand machines have been provided with means for feeding a continuous strip of paper which usually unwinds from a roll and passes to a shorthand printing device whereby a continuous series of shorthand characters are printed on the paper. It is, of course, a decided advantage to use a very long strip of paper, so that the writing may be continued for a considerable period of time without frequent interruptions; however, difficulty has been experienced in handling such paper after it passes from the machine. The paper is usually rewound on a rewinding roll, or torn from the machine in comparatively short lengths which are quite difficult to handle, and on account of their irregularity they cannot be readily filed for future reference. For obvious reasons, it would be very advantageous to file the shorthand notes in an orderly manner, so that any particular collection of notes could be found by referring to an index, and in this connection it would be highly desirable for all of the notes to be associated with an identification mark, designating the stenographer or dictator, or both. Many other advantages are to be gained by clearly identifying the dictator or stenographer, for instance, where a large concern employs a number of stenographers, each of which takes dictation from several different persons, it is quite convenient for a stenographer having a large collection of notes to transcribe, to be able to identify the dictator by merely glancing at the notes. This is an aid in transcribing the

notes, for it enables the stenographer to bear in mind the peculiarities or requirements of the particular dictator, and it also aids her in distributing the finished work to the different dictators. Moreover, by the use of means for printing identification marks in connection with the shorthand notes, an expert operator may be employed for the purpose of taking dictation which is to be transcribed by several different typists. In this event, the typists, after transcribing the notes, can readily distribute the finished work among the different dictators, for the identification marks on the different collections of notes will clearly identify the different dictators.

Therefore, the preferred form of my invention comprises, means for feeding a continuous strip of paper step by step; an automatic shearing device for cutting the paper into comparatively small sheets all of which are uniform in length; means for printing consecutive numbers on the small uniform sheets so that they may be readily indexed and filed for future reference or otherwise retained in the sequence indicated by the consecutive numbers; and means for printing at least one identification mark on each sheet of paper. All of these devices preferably operate automatically in response to movements of the finger keys, with the result of cutting the paper into uniform sheets, numbering the sheets consecutively, and printing an identification mark (or marks) on each sheet so as to clearly designate the dictator or stenographer, or both.

With the foregoing and other objects in view the invention comprises the novel construction, combination and arrangement of parts hereinafter more specifically described and illustrated in the accompanying drawings wherein is shown the preferred embodiment of the invention, however, it is to be understood that the invention comprehends changes, variations and modifications which come within the scope of the claims hereunto appended.

Figure I is a plan view, partly in section, illustrating a shorthand machine embodying the features of my invention.

Fig. II is a view similar to Fig. I showing mechanism which lies below the top wall of the housing.

Fig. III is a longitudinal section.

Fig. IV is a vertical section taken ap-

proximately on the line IV—IV, Fig. III, looking toward the front of the machine.

Fig. V is a detail view illustrating the paper feeding device.

5 Fig. VI is a section taken approximately on line VI—VI, Fig. I, showing the ribbon feeding device.

10 Fig. VII is a horizontal section showing the universal bar, the key levers associated therewith, and the ribbon feeding device operable by said universal bar.

Fig. VIII is a perspective view of the inking device for the numbering and identification wheels.

15 Fig. IX is an enlarged detail view showing the counting wheels having peripheral type characters, means for feeding said counting wheels, and the means for printing the consecutive characters.

20 Fig. X is a vertical section taken approximately through the center of the device shown in Fig. IX, showing the counting and identification wheels.

Fig. XI is a detail view of the identification wheel.

Fig. XII is an inverted plan view of the wheel shown in Fig. XI.

To illustrate the preferred form of the invention I have shown a shorthand machine provided with a housing 1, a type holder 2 arranged in said housing, (Figs. II and III) a type bar 3 detachably secured in said type holder, and a bi-color inking ribbon 4 adjacent to the line of type on said

35 type bar 3. The paper passes from a supply roll A, over a roller 5 (Fig. III) under and partially around a roller 5', in front of and over an uncurling device 6, and then to a paper feeding device whereby it is un-

40 wound from the roller and fed through an opening 7 at the rear of the machine. The key actuated devices preferably include a series of angular levers each having an upwardly extending arm 8 at its front end

45 (Fig. III) and a character key 9 at the upper end of said arm. Any suitable shorthand code may be used, and the character keys 9 are preferably, but not essentially provided with characters corresponding to

50 the line of type characters on the type bar 3.

The keyboard I have shown (Figs. I and II) includes three groups of keys bearing alphabetical characters and a fourth group of keys provided with numerical characters.

55 When one of the alphabetical keys is depressed, a corresponding alphabetical character is printed on the paper as will be hereinafter described. Each numeral key is associated with one of the alphabetical

60 keys, and when a numeral key is depressed, it shifts the bi-color inking ribbon, at the same time operating one of the alphabetical keys to print an alphabetical character in a distinguishing color, which indicates that

65 the alphabetical character is to be read as

a numeral. Each numeral key is fixed to a key lever a, pivotally supported at b (Fig. III) and fitted to a ribbon-shifting bar c, the latter being connected by means of vertical arms d, to a frame e which supports a pair of guide spools f. The frame e is an H shaped member pivotally supported at g, see Fig. II. The bi-color inking ribbon passes around the guide spools f, also around guide spools h, and it is fitted to a drive spool k. It will now be understood that when a numeral key lever a is depressed, the ribbon-shifting bar c moves downwardly, thereby moving the frame e about the axis of its pivot or fulcrum g, so as to lift the guide spools f, thus shifting the bi-color inking ribbon. The alphabetical keys G, F, D and M are provided with extensions 8' which lie under the numeral keys 1, 2, 3 and 4 respectively; the keys 85 M, L, T and F are provided with extensions 8' which lie under the numeral keys 7, 8, 9 and 0 respectively; the B key has an extension 8' which underlies the \$ key; and the keys O and E, near the middle of 90 the keyboard, have extensions 8' (Figs. II and III) which lie under the 5 and 6 keys respectively. These key extensions 8' and 8^a fitted to the numeral keys, are so arranged that one of the alphabetical keys 95 will move downwardly to print an alphabetical character in response to a corresponding movement of a numeral key.

The space key is secured to lever arms S which extend over the ribbon-shifting bar 100 c, said levers being pivotally supported by the pivot member b (Fig. III) and provided with extensions S' which engage a universal bar whereby the paper is fed step by step as will be hereinafter described. The error key (Figs. I and II) is fixed to a lever E, having an extension E' (Fig. III) which engages the ribbon shifting bar c, the object being to print the "error" character in a color which clearly distinguishes it from the ordinary shorthand characters.

110 Each of the angular key levers includes an arm 10 extending rearwardly from the arm 8 and an arm 11, extending upwardly from the rear portion of said arm 10. The series of key levers is pivotally supported by a pivot member 12 (Fig. III) located at the junctions of the lever arms 10 and 11. The upper end of each lever arm 11 is 115 provided with a forwardly extending printing hammer 13 which lies adjacent to the type 3, as seen most clearly in Figs. II and III. Restoring springs 14 (Fig. III) tend to retain the key levers in engagement with 120 an abutment 15. When one of the finger keys 9 is depressed, the key lever associated therewith turns about the axis of the pivot member 12 and the printing hammer 13 moves toward the type 3, thereby forcing 125 130

the paper and inking ribbon toward the type and printing one of the type characters on the paper. The key levers may be operated independently of each other, or 5 any desired number of key levers may be operated simultaneously.

16 designates a key lever guide near the upper ends of lever arms 11, and 17 designates a key lever guide located at the junctions of the lever arms 10 and 11.

10 The universal bar associated with the key levers includes a transverse abutment holder 18 (Figs. III and VII) arranged in front of the series of lever arms 11 and provided 15 with a yieldable abutment 19 which engages all of said lever arms 11. The universal bar also includes a pair of arms 20 and 21 pivotally supported by the pivot member 12, arranged on opposite sides of the lever 20 arms 11, and secured near their upper ends to the transverse abutment holder 18. 22 designates a connecting member uniting the arms 20 and 21 of the universal bar (Figs. III and VII), said connecting member being 25 located at the rear of lever arms 11. 23 designates a restoring spring (Fig. III) tending to retain the universal bar in the position shown in the drawings. The transverse abutment 19 forming part of the universal 30 bar structure is so arranged that the universal bar will move in response to movements of any one of the key levers.

The paper feeding device comprises a rotatable shaft 25, a pair of toothed wheels 26 and 27 fixed to said shaft, a ratchet wheel 28 also fixed to the shaft (Figs. II and V), and a pawl carrier 29 loosely secured to said shaft. 30 designates a pawl pivoted to the carrier 29 (Fig. V), and 32 designates a 35 spring connecting said pawl to the pawl carrier. The spring 32 tends to force the pawl into engagement with the ratchet wheel 28, as shown by dotted lines in Fig. V. The arm 21 of the universal bar is provided with 40 an extension 33 (Fig. V) which coöperates with an arm 35 on the pawl carrier 29. A spring 36, secured to the universal bar, tends to force the arm 35 into engagement with the universal bar extension 33, said arm 35 45 being so arranged between spring 36 and universal bar extension 33, that the pawl carrier will partake of the movements of the universal bar. It will be understood that the pawl carrier 29, as well as the universal 50 bar, is under the control of the key levers, and that the pawl carrier is adapted to oscillate in response to movements of said key levers.

When a key is depressed, or when several 55 keys are depressed simultaneously, the universal bar moves forwardly about the axis of pivot member 12, and the pawl carrier 29 turns about the axis of shaft 25 to advance the ratchet wheel 28 one step, thereby turning the toothed wheels 26 and 27 to unwind 60

the paper and advance it one step. At the end of the paper feeding operation, the printing hammer or hammers 13 force the paper and inking ribbon toward the type to print the selected character or characters. 70 Thereafter, the universal bar and key lever or levers, return to the positions shown in the drawings, and during this movement the paper feeding pawl 30 moves idly along the ratchet wheel 28.

75 The margins of the strip of paper are preferably perforated as shown in Fig. I to receive the teeth which project from the periphery of the feed wheels 26 and 27. 38 designates a pressing device (Figs. I and 80 III) pivotally secured to stationary arms 39 and adapted to engage the paper at points near the teeth of the feed wheels 26 and 27 to prevent the paper from becoming disengaged from said feed wheels during the 85 paper feeding operations.

The inner end of the strip of paper is firmly secured to a tubular core 40 (Figs. II and III) provided at its ends with friction members 41 and 42 which turn with the roll 90 of paper, said friction members being secured to the core in any suitable manner. A non-yielding friction member 43, engaging the friction member 41, is rigidly secured to a stationary arm 44. 45 designates 95 a yieldable friction member slidably fitted to a spring pocket at the end of a stationary arm 46. A spring 47 forces the friction member 45 into engagement with the friction member 42 which turns with the supply roll, at the same time forcing the friction member 41 into engagement with the stationary friction member 43.

100 The spring pressed friction elements tend to prevent the roll of paper from turning, and upon the operation of the paper feeding device, the paper is pulled along the uncurling device 6, (Fig. III) the latter being a very small rod fixed to the arms 39. In passing over the uncurling device, the strip 110 of paper is turned abruptly in the direction opposed to the direction in which it was wound on the roll. By holding the paper under tension and pulling it over the uncurling device in the manner illustrated, the 115 paper is uncured and fed from the machine in an absolutely straight condition.

The automatic shearing device includes a stationary blade 51 and a movable blade 52 located near the rear of the machine and 12 adapted to sever the paper after it passes from the printing, uncurling and feeding devices. This automatic device is preferably under the control of the character keys, and it is preferably constructed to automatically 12 cut the paper into a series of short uniform strips, which may be easily handled by the operator and readily filed for future reference. The consecutive numbering device and the devices for printing identification 13

marks are preferably coöperable with the automatic shearing device, all of said devices being under the control of the character keys, and the operating means being 5 preferably so constructed that the said shearing, and numbering and identification devices operate simultaneously. The consecutive numbering device is adapted to print serial page numbers, one of which appears on 10 each of the strips of paper. In this connection it may be noted that the combination of the uncurling device, the shearing device, the consecutive numbering device, and the identification device, produces a very 15 desirable result, for if the paper was not straightened, the small sheets passing from the shearing device would, on account of their tendency to recurl, be quite difficult to handle; and since each of the small straight 20 sheets bears a serial number or page number, together with a mark identifying the stenographer or dictator, the series of sheets may be readily bound together and indexed for future reference. If the sheets accidentally 25 become disarranged, they may be easily replaced in their proper relative positions by arranging them in the sequence indicated by their page or serial numbers. If desired, 30 all of the sheets bearing the same identification mark may be bound together, thus providing an individual collection of sheets for each dictator.

Briefly stated, the means for operating the automatic shearing, numbering and 35 identification devices comprises an operating spring for moving the blade 52 and at the same time actuating certain printing elements to print the numbers and identification marks; means for transmitting energy 40 from the finger keys to said operating spring so as to place the latter under tension, and a restoring spring for returning the blade 52. These automatic devices are under the control of a timing device which moves step 45 by step in response to movements of the finger keys, and upon the completion of a predetermined number of paper feeding operations, the timing device reaches a position wherein it will permit the operating spring 50 to actuate the shearing, numbering and identification devices.

The movable blade 52 (Fig. IV) is secured to a frame at the rear of the machine by means of a pivot member 53, and it is provided with an extension 54 adapted to be 55 engaged by a trippable operating member 55, the latter being pivoted at its lower end to a lever 56. This lever is pivoted at 57, and is provided with a finger 58 which engages a timing cam 59, see Figs. III and IV. 60 Designates an operating spring secured to the cam driven lever 56 and also secured to a stationary part of the machine. The timing cam 59 moves step by step in response 65 to operations of the character keys, as will

be hereinafter described, thereby lifting the lever 56 and placing the operating spring 60 under tension. When the shoulder 59', on cam 59, reaches the point of finger 58, the operating device is released and the 70 spring 60 then pulls the trippable operating member 55 downwardly so as to force the movable blade 52 into engagement with blade 51. A restoring spring 61, connecting the movable blade to the lever 56, is 75 placed under tension during the cutting operation, however, this spring is not effective until the movable blade is released from the trippable operating member 55. The means for releasing the trippable member 55 comprises a cam 62 formed on said member 55 and adapted to engage a roller 63. 64 designates a spring connecting the trippable member 55 to the lever 56 and tending to force the cam 62 into engagement with roller 63. 80 The upper end of the trippable member 55 has an extension 55' adapted to bear upon the blade extension 54 and adapted to be disengaged therefrom by moving said trippable member downwardly from the position 85 shown in Fig. IV. During this downward movement the cam face 62 moves along the roller 63 so as to release the trippable member 55 from blade 52, thus permitting the restoring spring 61 to return said blade. The 90 operating spring 60 is of sufficient strength to actuate the movable cutter and at the same time place the restoring spring 61 under tension.

When the cam lever 56 is thrown by the 100 operating spring 60, it strikes a pad 67 which prevents the cam finger 58 from striking the cam 59, thus deadening the hammer blow near the free end of lever 56 and avoiding a noisy hammer blow at the cam 105 59. As the cam 59 continues to advance, it engages the cam finger 58 in a noiseless manner, and the cam lever 56 is gradually shifted to restore the operating spring 60 and the trippable shear operating member 55 to 110 the positions shown in Fig. IV. In moving to this position, the trippable operating member 55 travels slowly along the roller 63 until the inclined face 55^a, at the upper end of said member 55, engages the blade extension 115 54. The trippable member 55 then moves upwardly and away from roller 63, and its extension 55' finally passes over the blade extension 54, to the position shown in Fig. IV. The member 55 is pulled to the last 120 mentioned position by the small spring 64, and instead of striking a hammer blow on the roller 63, said member 55 strikes a pad 68. Thereafter, the shoulder 59' on the timing cam 59 reaches the cam finger 58, and 125 the operating spring 60 then actuates the movable blade as previously described.

The means for driving the timing cam 59 (Figs. II and IV) comprises a ratchet wheel 69 secured to said cam, and also se- 130

cured to a sleeve 70, the latter being fixed to a shaft 71. 72 designates a rocker arm loosely supported by the sleeve 70 and provided with a pawl 73 which engages the ratchet wheel 69. A bell crank lever 74, pivotally supported at 75, is provided with a pad which engages the rocker arm 72. 77 designates a yieldable link connecting the universal bar to the bell crank lever 74, see Fig. III.

10 During each paper feeding operation, the universal bar turns about the axis of its pivot member 12 to actuate the paper feeding device, at the same time operating link 77, bell crank lever 74, rocker arm 72 and pawl 73, so as to advance the ratchet wheel 69 and timing cam 59 one step. During the return movement of the universal bar, the pawl 73 moves idly along the toothed face of ratchet wheel 69, and the ratchet wheel 20 is prevented from turning backwardly by a retaining pawl 78, shown in Fig. IV. The rocker arm 72 is preferably connected to bell crank 74 by a spring 79 (Fig. IV) which retains said parts in frictional engagement with each other.

The consecutive character printing device, shown most clearly in Figs. IX and X, preferably comprises units, tens, and hundreds wheels, designated U, T and H, respectively, arranged within a small housing 81, and rotatably fitted to a tubular member 82, each of said wheels being preferably in the form of a ring having a series of uniform notches 83 and a comparatively deep 30 notch 84, see Fig. IX. Each of these counting wheels is also preferably provided with peripheral type characters for printing the characters 0 to 9 as indicated in Fig. IX. The means for feeding the counting wheels 40 comprises a rockable pawl carrier having a pair of arms 85 which lie within the housing, shaft members 86 and 87 extending from said arms, and a curved web 88 connecting said arms. The shaft members 86 45 and 87 are journaled to the side walls of the housing 81. A combined feeding and carrying pawl 89, arranged within the counting wheels, is flexibly connected to the arms 85 by means of a link 90. 91 designates a spring for forcing the pawl 89 into engagement with the notched faces of the counting wheels. 92 designates spring 50 pressed retaining pawls adapted to enter the notches of the counting wheels to prevent 55 said wheels from moving beyond the lining point during the return movement of feed pawl 89.

The combined feeding and carrying pawl 89 is provided with a stepped operating 60 edge adapted to enter the notches of the different counting wheels. The different steps of the pawl are uniform in depth, the shallow notches 83 of each wheel being uniform, and the enlarged or comparatively deep 65 notch 84 being adapted to receive the stepped pawl during the carrying operations. 93 designates an operating arm for oscillating the pawl carrier and pawl 89, so as to feed the counting wheels step by step. When the parts occupy the positions shown in Figs. 70 IX and X, all of the deep notches 84 are one step in advance of the combined feeding and carrying pawl 89, and the type characters 000 appear at the printing point. The pawl 89 engages the units wheel U, and it 75 is disengaged from the remaining wheels as seen in Fig. X. At the beginning of the counting operations, the units wheel advances step by step in response to the oscillatory movements of operating arm 93, and 80 after the units wheel has advanced nine steps, the pawl 89 enters the deep notch 84 of the units wheel, at the same time entering a shallow notch in the tens wheel. The movement of the pawl is limited by the tens 85 wheel, so that its operating edge does not, at this time, enter the hundreds wheel. The tens wheel as well as the units wheel will then move one step with the pawl, and upon the completion of such movements the characters 90 95 100 105 110 115 120 125 130 99 will appear at the printing point. The tens wheel advances one step during each revolution of the units wheel, and after the tens wheel has advanced nine steps its deep notch 84 will register with the deep notch of the units wheel, thus permitting the stepped pawl to engage all of the counting wheels. At this time the characters 99 appear at the printing line, and a continued movement of the pawl carrier will result in 100 moving all of the counting wheels simultaneously to locate the characters 100 at the printing point. Obviously, the hundreds wheel will advance one step during each revolution of the tens wheel. While I have 105 shown three counting wheels it is to be understood that any desired number of counting wheels may be used and that any desired printing characters may be formed on the counting wheels. Furthermore, any 110 desired means for feeding the wheels may be substituted for the mechanism just described.

I designates an identification device, in the form of a ring located alongside of the 115 counting wheels, and provided with peripheral type characters.

The counting mechanism moves one step in response to a predetermined number of key operations, said counting mechanism 120 being under the control of the timing cam 59 and cam lever 56, shown in Fig. IV. 94 designates a link connecting the operating arm 93 of the counting mechanism to a lever 95, the latter being pivotally mounted on a 125 stationary rod 96. A link 97 connects the lever arm 95 to the cam lever 56, see Fig. IV. During each revolution of the timing cam 59, the lever arm 56 rises to the position seen in Fig. IV, and is then pulled down-

wardly by the operating spring 60 as previously described. Motion is transmitted from the cam lever 56 through the medium of link 97, lever arm 95, link 94, and operating arm 93, so as to feed the counting wheels during the upward movements of cam lever 56. When the cam lever moves downwardly, the carrying pawl of the counting mechanism is restored very quickly while it is frictionally engaged with at least one of the counting wheels. Thereby alining the counting wheel or wheels immediately before the printing operations.

The means for printing the identification mark and the consecutive numbers comprises an inking web or ribbon 98 arranged above the strip of paper A', and a platen 99 arranged below the paper at a point immediately below the ribbon, and also below the identification device and counting wheels. Platen 99 is preferably a piece of rubber or other yieldable material fitted to a platen carrier 100, the latter being a lever arm supported by a pivot rod 101 and provided with a yieldable stop member adapted to engage a stationary member 102, as shown in Fig. IX. The means for operating the platen carrier 100 comprises a hammer 103 loosely supported by the pivot rod 96 and provided with a pad 104 adapted to engage the platen carrier as indicated by arrows in Fig. IX. A flexible link 105, preferably made of cloth, leather, or other fibrous material, connects the hammer 103 to the cam lever 56, see Figs. IV and IX. When the cam lever 56 is thrown downwardly by the operating spring 60, the flexible link is jerked very quickly to throw the hammer 103 into engagement with the platen carrier 100, thereby printing one of the consecutive numbers upon the paper. The hammer 103 is impelled by momentum when it strikes the platen carrier, the flexible link 105 being free to yield to permit such movement after the cam lever 56 has been stopped by the abutment 67. After striking the platen carrier 100, the hammer 103 drops by gravity to the position below said platen carrier, where it will permit the latter to return to the position shown in the drawings. The downward movement of hammer 103 is limited by the flexible link 105, the latter being straightened during this movement.

From the foregoing it will be understood that the counting mechanism, the printing mechanism associated with the counting and identification devices, and the automatic shearing device, are all under the control of the timing cam 59, and upon the completion of a predetermined number of key operations, or paper feeding operations, the shearing device is actuated to sever the paper and the automatic printing device is actuated to print an identification mark and one of the consecutive numbers on the paper at a point

in front of the shearing device. Each of the comparatively small sheets of paper passing from the machine bears a serial or page number and an identification mark which are printed by the automatic printing device. 70

The timing cam 59 is fixed to a rotatable shaft 71, said shaft being exposed at the rear of the machine, as shown in Fig. II. The rear end of shaft 71 is adapted to receive a key or other operating member which may be turned to actuate a timing device independently of the finger keys. One of the objects of the invention is to cut the paper into uniform sheets each bearing a page number and an identification mark, and it is 80 therefore desirable to provide a convenient means for cutting the paper without operating the character keys and paper feeding device. When a new roll of paper is applied to the machine, the strip is fed, by hand, between the shear blades and through the discharge opening at the rear end of the machine. The operator then turns the cam shaft 71, by hand, so as to actuate the shearing and printing devices, thereby severing the paper, printing an identification mark and a serial number on the strip at a point in front of the shear; and at the same time placing the timing device in its starting position so that the first sheet will be equal in 95 length to all of the other sheets.

The inking ribbon located between the consecutive numbering device and platen 99, is preferably a small web of fabric 98 secured to a ribbon holder 107 (Fig. VIII), 100 said ribbon holder being provided with a slot for the reception of a screw 108 which is exposed near the rear of the machine, as shown in Fig. I. Lever arm 109, shown by dotted lines in Fig. I, is arranged within 105 the main housing and pivotally connected to the ribbon holder 107 through the medium of a screw 110 which passes through a slot formed in a top wall of the housing. The ribbon holder may be readily detached and removed from the machine by removing the screws 108 and 110. A lever arm 109', connected to the arm 109 (Figs. I and VI) engages an eccentric 111, the latter being fixed to a shaft 112 which turns step by step to 115 feed the small ribbon 98, as will be presently described. The lever arm 109' is moved in one direction by the eccentric 111, and it may be restored by means of a spring shown by dotted lines in Fig. I. 120

113 designates a ratchet wheel fixed to the shaft 112, and 114 designates an oscillatory pawl carrier loosely fitted to said shaft, the pawl carrier being provided with a pawl which engages the teeth of said ratchet 125 wheel. A yieldable link 115 connects the pawl carrier 114 to the arm 21 of a universal bar, as shown in Figs. I and VII. The universal bar oscillates in response to movements of the key levers, so as to oscillate the 130

pawl carrier 114, thereby feeding the ratchet wheel 113, step by step to actuate the ribbon feeding eccentric 111.

The inking ribbon 4, which travels between the type bar 3 and printing hammers 13, is preferably a continuous web of material fitted to the feed spool *k*, the latter being fixed to the vertical shaft 112 which is operated through the medium of the universal bar as previously described.

The identification ring or wheel I, located in the small housing 81, is supported by the tubular member 82, and it is provided with a series of notches 120 adapted to receive a spring pressed pawl or detent 92' (Fig. X). This identification member I (Fig. XI) is formed with peripheral type characters A, B, C, D, E, F, G, H, I and J, any one of which is adapted to be positioned at the printing point so as to print a character designating the stenographer or dictator. The identification member is also provided with indicator characters at points between the type characters as shown in Fig. XI, and the small housing 81 is provided with a sight opening 121 at a point opposite the identification member. The indicator character appearing at the sight opening 121 corresponds with the type character at the printing point. The operator may readily adjust the identification wheel to print any of the identification characters, by inserting a pencil, or other device, through the sight opening 121 and turning the identification wheel until the desired indicator character appears at the sight opening.

In carrying out the invention, I preferably use the identification wheel as the means for identifying the dictators. The stenographer may be identified by the color of the printing, and the inking device 107 (Figs. I and VIII) is therefore so constructed that it may be very easily applied to or removed from the machine. It is to be understood, however, that any suitable marks or characters may be used for the purpose of identifying the dictators and stenographers, and that the means for making such marks or characters on the paper may be located at any suitable point near the path of the paper.

The printing hammers and the type holding elements associated therewith are claimed in an application for patent filed by me on Nov. 18, 1916, Serial No. 132,076. The key lever guide is claimed in an application filed by myself and W. E. Lippert on Nov. 18, 1916, Serial No. 132,077. The universal bar is claimed in an application filed by myself and W. E. Lippert on Nov. 18, 1916, Serial No. 132,078. The ribbon feeding mechanism is claimed in an application filed by me on Nov. 18, 1916, Serial No. 132,075, and also in an application filed by myself and W. E. Lippert on Nov. 18, 1916, Serial No.

132,073. The automatic cutting device is claimed in an application filed by me on Nov. 18, 1916, Serial No. 132,071. The automatic numbering device is claimed in an application filed by me on Nov. 18, 1916, Serial No. 132,072. The paper straightening device is claimed in an application filed by me on May 19, 1917, Serial No. 169,620. The paper feeding device is claimed in an application filed by myself and W. E. Lippert, on Nov. 18, 1916, Serial No. 132,066. Reference is also made to applications filed by me on Feb. 21, 1917, Serial Nos. 150,052, 150,053, 150,054 and 150,055, respectively, and to an application filed by me on Nov. 18, 1916, Serial No. 132,062, each of which claims shift keys combined with shorthand machine keys.

I claim:

1. In a shorthand machine adapted to receive a strip of paper, a shorthand printing device, keys for operating said shorthand printing device, and means for printing an identification mark on the paper at regular intervals in response to movements of said keys, said means including an adjustable type wheel under the control of the operator, said adjustable type wheel being provided with a series of identification characters.

2. In a shorthand machine adapted to receive a strip of paper, a shorthand printing device, keys for operating said shorthand printing device, a consecutive numbering device for printing consecutive numbers on said strip of paper at regular intervals in response to movements of said keys, and an identification member for printing an identification mark on the paper at regular intervals in response to movements of said keys, said identification member being adjustable independently of said consecutive numbering device.

3. In a shorthand machine adapted to receive a strip of paper, a shorthand printing device, keys for operating said shorthand printing device, a consecutive numbering device for printing consecutive numbers on the paper at regular intervals, said consecutive numbering device including counting wheels movable step by step in response to movements of said keys, and an identification wheel associated with said counting wheels and adapted to print an identification mark on the paper at regular intervals, said identification wheel being provided with a series of type characters for printing different identification marks, the said counting wheels being under the control of said keys and the identification wheel being adjustable independently of said counting wheels.

4. In a shorthand machine adapted to receive a strip of paper, a shorthand printing device, keys for operating said shorthand printing device, and an identification device

for printing an identification mark on the paper, said identification device including a type wheel provided with a series of type characters representing different identification marks and also provided with a series of indicator characters corresponding to said type characters.

5. In a shorthand machine adapted to receive a strip of paper, printing elements including finger keys, and means for printing an identification mark at regular intervals in response to movements of said keys.

10. In a shorthand machine adapted to receive a strip of paper, printing elements including finger keys, and means for printing an identification mark and a serial number at regular intervals in response to movements of said keys.

15. In a shorthand machine adapted to receive a strip of paper, a shorthand printing device including finger keys, a paper feeding device operable by said keys, and an identification device for printing an identification mark on the paper, the printing elements of said identification device being operable by said keys.

20. In a shorthand machine adapted to receive a strip of paper, a shorthand printing device including finger keys, a paper feeding device operable by said keys, and an identification device for printing an identification mark on the paper, the printing elements of said identification device being operable automatically upon the completion of a predetermined number of key operations.

25. In a shorthand machine adapted to receive a strip of paper, a shorthand printing device including finger keys, a paper feeding device operable by said keys, and an identification device for printing an identification mark on the paper, the printing elements of said identification device including an operating spring and means for transmitting energy from said keys to said operating spring.

30. In a shorthand machine adapted to receive a strip of paper, a shorthand printing device including finger keys, a paper feeding device operable by said keys, and an identification device for printing an identification mark on the paper, the printing elements of said identification device including an operating spring and means for transmitting energy from said keys to said operating spring, said means including a transmission member movable step by step in response to operations of said keys.

35. In a shorthand machine adapted to receive a strip of paper, a shorthand printing device including finger keys, a paper feeding device operable by said keys, and an identification device for printing an identification mark on the paper, the printing elements of said identification device including an operating spring, and means for transmitting

energy from said keys to said operating spring, said means including a ratchet and pawl movable step by step in response to operations of said keys.

40. In a shorthand machine adapted to receive a strip of paper, a shorthand printing device, finger keys for operating said printing device, and an identification device for printing identification marks on the paper, said identification device including a type member, a platen movable toward said type member, and means for operating said platen automatically upon the completion of a predetermined number of key operations.

45. In a shorthand machine adapted to receive a continuous strip of paper, a shorthand printing device, keys for operating said shorthand printing device, an automatic shearing device for cutting the paper into substantially uniform sheets, said automatic shearing device being operable at regular intervals in response to movements of said keys, and an identification device for printing an identification character on the paper at regular intervals in response to movements of said keys.

50. In a shorthand machine adapted to receive a continuous strip of paper, a shorthand printing device, keys for operating said shorthand printing device, an automatic shearing device for cutting the paper into substantially uniform sheets, said automatic shearing device being operable at regular intervals in response to movements of said keys and an identification device adapted to mark the paper.

55. In a shorthand machine adapted to receive a continuous strip of paper, a shorthand printing device, keys for operating said shorthand printing device, an automatic shearing device for cutting the paper into substantially uniform sheets, said automatic shearing device being operable at regular intervals in response to movements of said keys and an identification device adapted to mark the paper, said identification device including printing means under the control of said keys.

60. In a shorthand machine adapted to receive a continuous strip of paper, a shorthand printing device, keys for operating said shorthand printing device, an automatic shearing device for cutting the paper into substantially uniform sheets, said automatic shearing device being operable at regular intervals in response to movements of said keys and an identification device for printing identification marks on the paper, said automatic shearing device and identification device being so arranged that an identification character will appear upon each sheet of paper.

65. In a shorthand machine adapted to receive a continuous strip of paper, a shorthand printing device, an automatic shearing

- device for cutting the paper into comparatively short sheets, an identification device including printing elements for printing identification characters on the paper, said 5 identification device being so arranged that an identification character will appear upon each of said comparatively short sheets of paper, and operating means common to all of said devices.
- 10 18. In a shorthand machine adapted to receive a continuous strip of paper, a short-hand printing device, an automatic shearing device for cutting the paper into comparatively short sheets, an identification device 15 including printing elements for printing identification characters on the paper, said identification device being so arranged that an identification character will appear upon each of said comparatively short sheets of 20 paper, and operating means common to all of said devices, said operating means including finger keys and means for transmitting energy from said finger keys to all of said devices.
- 25 19. In a shorthand machine adapted to receive a continuous strip of paper, a short-
- hand printing device, an automatic shearing device for cutting the paper into comparatively short sheets, an identification device including printing elements for printing 30 identification characters on the paper, said identification device being so arranged that an identification character will appear upon each of said comparatively short sheets of paper, and operating means common to all 35 of said devices, said operating means including finger keys, a universal bar under the control of said finger keys, and means for transmitting movement from said universal bar to said shearing and identifica- 40 tion devices.
20. In a shorthand machine adapted to receive a strip of paper, a printing device, finger keys for actuating said printing device, an identification device adapted to 45 mark the paper so as to identify the operator of the machine, and actuating means for said identification device, said actuating means including a universal bar driven by said finger keys.

WARD S. IRELAND.
